UNITED STATES PATENT OFFICE.

ALFRED W. BRUCE, OF NEW YORK, N. Y.

LOCOMOTIVE CYLINDER SADDLE.

Application filed July 5, 1924. Serial No. 724,534.

To all whom it may concern:

Be it known that I, ALFRED W. BRUCE, a citizen of the United States, and a resident of the city, county, and State of New York, have invented a certain new and useful Improvement in Locomotive Cylinder Saddles, of which improvement the following is a specification.

My invention relates to locomotive engines of the three cylinder type, and its object is to provide means for connecting the cylinders thereof to the boiler and frame members, which shall present the advantages of reduction of structural cost, and of finished weight, within the limits of sufficient strength, and symmetrical disposition of constituent members.

The improvement claimed is hereinafter fully set forth.

20 In the accompanying drawing: Figure 1 is a side view, in elevation, of a saddle for a three cylinder locomotive engine, illustrating an embodiment of my invention; Fig. 2, a front view, in elevation, of the 25 same; Fig. 3, a horizontal section, on the line *a a* of Fig. 2; Fig. 4, a vertical section, on the line *b b* of Fig. 2; Fig. 5, a side view, in elevation, of a saddle showing a structural modification; Fig. 6, a front 30 view, in elevation, of the same; and, Fig. 7, a vertical section, on the line *c c* of Fig. 6.

In the practice of my invention, referring descriptively to the specific embodiment thereof which is herein exemplified, and first to Figs. 1 to 4 inclusive, the saddle comprises a body, 1, having bottom flanges, 1^a, adapted to fit against the side members, A A, of a locomotive frame, and a smoke box seat, 1^b, at its top, concavely curved, on 35 the radius of the smoke box, B, of a locomotive boiler, which the saddle is designed to support, and to which, in service, it is connected in the usual manner.

A middle cylinder, 2, and a distribution 45 valve chest, 3, therefor; two side cylinders, 2^a, 2^b; and distribution valve chests, 3^a, 3^b, for said cylinders, respectively, are cast integral with the body, 1, of the saddle, the side cylinders being located symmetrically 50 in the body, relatively to its middle vertical plane, with which they are parallel. Steam from the boiler is conveyed to all three distribution valve chests through steam supply pipes, C, C, extending outwardly from the smoke box, in the present 55 standard manner, said pipes being connected

to short supply nozzles, 4^a, 4^b, also integral with the body of the saddle, and projecting upwardly therefrom, above the valve chests, 3^a, 3^b, of the side cylinders. The 60 supply nozzles communicate with the ends of a transversely extending steam supply conduit, 4, cored in the body, said conduit being continuously in open communication 65 with the middle portion of each of the distribution valve chests, 3, 3^a and 3^b. Exhaust passages, 5^a, 5^b, lead from the end portions of the valve chests, 3^a, 3^b, of the side cylinders to the smoke box seat, 1^b, and exhaust passages, 5, lead from the end portions of the valve chest, 3, of the middle cylinder, to the smoke box seat. Exhaust 70 pipes and nozzles, of any suitable and preferred construction, which do not form part 75 of my present invention, are, in service, connected to the ends of the exhaust passages.

The bottom of the body of the saddle is machined, to form plane faces thereon, which abut against the side members, A, A, of the locomotive frame, to which the 80 saddle is rigidly attached, by bolts, 6. The body is preferably recessed at its bottom, to fit over the frame members, as shown, and has strengthening flanges, 1^c, adjoining 85 them, on its front and rear sides.

The modification shown in Figs. 4 to 7 inclusive, differs from the construction hereinabove described, in the minor structural particulars that the middle cylinder, 2, is downwardly and rearwardly inclined, instead of being disposed horizontally as in the construction first described, and its valve chest, 3, is located on one side, instead of above it. As a result of such relative disposition of the middle cylinder and valve 90 chest, the transverse steam supply conduit, 4, may, as shown, extend only between the valve chest of one of the side cylinders, and the valve chest, 3, of the middle cylinder. The bottom of the body of the saddle, in 95 this modified form abuts only on the top and outer sides of the frame members, instead of being recessed to fit over them, as in the construction first described.

It will be recognized by those familiar with 100 locomotive construction and operation, that the cylinder saddle herein set forth, desirably complies with the requirements of a structure for supporting the cylinders and boiler of a three cylinder locomotive and 105 connecting them to the frame members. The construction of the body, the cylinders,

- and the distribution valve chests, in an integral casting, reduces, to a substantial extent, the weight and the cost of manufacture of the structure, by eliminating the machine work and bolting required in the two piece and three piece saddles of the present designs and also a simpler and more direct disposition of steam and exhaust passages, is rendered practicable.
- 5 10 I claim as my invention and desire to secure by Letters Patent:
1. A cylinder saddle for three cylinder locomotives, comprising a body, having plane faces at its bottom, adapted to abut against frame members; a middle cylinder and two side cylinders, disposed symmetrically in the body and integral therewith; and distribution valve chests, integral with the body, each adjoining one of the cylinders.
  - 15 20 2. A cylinder saddle for three cylinder locomotives, comprising a body, having plane faces at its bottom, adapted to abut against frame members; an inclined middle cylinder and two horizontal side cylinders, all integral with the body; a distribution valve chest at one side of the middle cylinder, and a distribution valve chest above each of the side cylinders; nozzles on the valve chests of the side cylinders, adapted to receive boiler steam; and a steam supply conduit, connecting one of said nozzles with the distribution valve chest of the middle cylinder.
  - 25 30 35 40 45 3. A cylinder saddle for three cylinder locomotives, comprising a body, having plane faces at its bottom, adapted to abut against frame members; an inclined middle cylinder and two horizontal side cylinders, all integral with the body; a distribution valve chest at one side of the middle cylinder, and a distribution valve chest above each of the side cylinders; nozzles on the valve chests of the side cylinders, adapted to receive boiler steam; and a steam supply conduit, extending transversely and downwardly from one of said nozzles, and connecting said nozzle with the distribution valve chest of the middle cylinder.

ALFRED W. BRUCE.
